UNITED STATES PATENT OFFICE

112,098

DESIGN FOR A DRESS

Jacob Abbate, New York, N. Y.

Application September 21, 1938, Serial No. 80,014

Term of patent 3½ years

To all whom it may concern:

Be it known that I, Jacob Abbate, a citizen of the United States and a resident of the city of New York, in the county of New York and State of New York, have invented a new, original, and ornamental Design for a Dress, of which the following is a specification, reference being had to the accompanying drawing, constituting a part thereof.

Fig. 1 is a front view of a dress showing my new design.

Fig. 2 is a rear view of the dress shown in Fig. 1.

The characteristic feature of my design resides in the specific "air tucked" quilting on the upper waist and sleeve portions of the dress disclosed in combination with the tucked and pleated skirt as shown.

I claim:

The ornamental design for a dress, substantially as shown and described.

JACOB ABBATE.
